UNITED STATES PATENT OFFICE.

JOHN JOSEPH ORMOND, OF MATTAPAN, BOSTON, MASSACHUSETTS, ASSIGNOR TO JOHN JOSEPH ORMOND, JOSEPH J. CALLAHAN, AND HERBERT A. GILLMAN, AS TRUSTEES OF THE ORMOND MULTICOLOR PRINTING COMPANY, A COMMON LAW TRUST OF MASSACHUSETTS.

METHOD OF AND MACHINE FOR PRINTING BY TRANSFER.

Application filed July 25, 1923. Serial No. 653,727.

To all whom it may concern:

Be it known that I, JOHN J. ORMOND, a citizen of the United States, residing at Mattapan, Boston, in the county of Suffolk and State of Massachusetts, have invented certain new and useful Improvements in Methods of and Machines for Printing by Transfer, of which the following is a specification, reference being had to the accompanying drawings, forming a part thereof.

My invention relates to methods of and machines for printing by transfer and has for its object to provide a method and machine by which a transfer medium may be caused to take up ink from the inked surface of one or more printing plates, transfer the ink so taken up to the surface of the sheet of material or other article to be printed, have the surplus ink removed from its surface and again take up ink from the surface of the printing plate or plates upon its cleaned surface and again transfer the ink so taken up to the surface of a second article to be printed, by a continuous operation. A further object of the invention is to provide a method and machine by which the transfer medium may be caused to successively take up ink from the inked surfaces of a series of printing plates, each forming a part only of a complete design and each adapted to be inked with ink of a different color, in such relative position upon the surface of the printing medium that when transferred to the surface of the article to be printed a complete design will be imprinted thereon with all of the several parts in accurate registry by a single operation. A further object of the invention is to provide a method and machine by which the ink upon the printing surfaces of the several printing plates will be taken up by the transfer medium whether or not the printing surfaces of the several printing plates are in the same horizontal plane. A further object of the invention is to provide a method and machine by which the printing of the complete design will be effected upon the article to be printed whatever the material may be and whatever its thickness, if of sheet material, may be. A

further object of the invention is to provide a machine adapted to be operated by power by which successive prints from printing plates may be made by the same printing roller by continuous operation of the machine without the necessity of doing by hand, or by mechanism other than that of the machine in which my invention is embodied, anything except to ink the printing plates and supply the article to be printed and remove it after it is printed. A further object of the invention is to provide means by which the transfer printing roller may be moved in a continuous operation over the printing plates and the article to be printed into contact with means for removing surplus ink and otherwise cleaning its surface, and again moved over the printing plates to repeat the printing operation. A further object of the invention is to provide a construction by which, as the transfer printing roller is moved over the printing plates, its rotation will be determined by its progressive movement so that its surface will have rolling contact only with the printing plates, and as it is moved in contact with the cleaning means it will be positively rotated at a rate of speed independent of its progressive movement. A further object of the invention is to provide means by which the rotation of the transfer printing roller while in contact with the cleaning means is arrested on the completion of the cleaning operation before being again moved over the printing plates.

With the objects above indicated and other objects hereinafter described in view my invention consists in the method and machine hereinafter described and claimed, it being understood that the method of my invention is not in any way limited or restricted to the use, for the purpose of carrying it out, of the particular machine shown and described.

Referring to the drawings:

Figure 1 is a perspective view of the operating parts of a power operated printing machine embodying my invention.

Figure 2 is a top plan view of the same

printing machine embodying my invention,

Figure 2^a is a view of a design as printed on the machine shown in Figures 1 and 2,

Figure 3 is a side view of the machine shown in Figures 1 and 2,

Figure 4 is a central longitudinal sectional view of the same machine,

Figure 5 is a cross sectional view on line 5—5 of Figure 4,

10 Figure 6 is a detail side view partly in section showing the transfer printing roller in contact with the ends of the guide rails in the position in which its rotation is arrested,

15 Figure 7 is a perspective view of the rotary disc for cleaning off ink from the transfer printing roller.

Figure 8 is a detail cross sectional view on the same line 5—5 of Figure 4 on which

20 Figure 5 is taken but on an enlarged scale and showing the transfer printing roller in contact with the cleaning belt, and

Figure 9 is a detail side view of the gearing for driving the shaft which carries the 25 pulleys on which are carried the belts for rotating the transfer printing roller during the cleaning operation.

In the drawings 1 indicates a base plate adapted to support a series of printing 30 plates of which three are shown, indicated by 2, 2' and 2'', and a holder or support 4 for the plate, sheet or other article on which the complete design is to be printed as shown in Figure 2^a.

35 Figure 5 indicates a transfer printing roller of suitable composition carried on a core 6, the ends of which are adapted to serve as journals on which the roller may rotate freely, and adapted when rolled over the printing plates to take up 40 from their printing surfaces the ink previously applied to these surfaces and, when rolled upon the plate, sheet or other article in the holder 4, to deposit upon it the ink so taken up.

45 The composition of which the transfer printing roller is formed is similar to that used in inking rollers but preferably slightly harder or tougher than the composition commonly used for inking rollers.

50 The base plate 1 is supported between side plates 7 and 8 by a suitable cross bar 9 preferably formed integral with the side plates. Near their ends these side plates 7 and 8 are provided with bearings for shafts 55

10 and 11 each of which carries a pair of sprocket wheels 12, 12, and 13, 13, just inside the lines of the inner faces of the side plates. The bearings for shaft 11 are stationary and this shaft is provided outside

60 the side plate 8 with a pulley 14 arranged to be driven by belt 15 from any convenient source of power. The bearings for shaft 10 are made adjustable. In the construction shown these bearings 16 are ar-

65 ranged to be slidable in ways 17 on the side

plates and may be forced outward to tighten the sprocket chains by screws 18 working in lugs 19. On the sprocket wheels are carried sprocket chains 20 and 21 each provided with a bearing block 22 and 23 respectively, 70 for the ends of the core 6 of the transfer printing roller 5. The two sprocket chains 20 and 21 are so adjusted that their bearing blocks 22 and 23 are in a line at right angles to the line of movement of the 75 sprocket chains. The diameters of the sprocket wheels and the location of the bearings for the shafts which carry them are such that the transfer printing roller 5 will be carried over the base plate 1 in such relation thereto that the peripheral surface of the roller will contact with the printing surfaces of the printing plates in its forward or printing movement, and will be brought back beneath the base plate and its supporting cross bar 9 on its return movement. 80

85 On the base plate parallel with but a substantial distance within its longitudinal edges, are arranged guide rails 25 and 26. These guide rails extend the full length, or 90 nearly the full length, of the base plate, they are "type high" that is, their upper faces are in the horizontal plane of the printing surfaces of the printing blocks, and these upper faces are level from end to end. In 95 the printing operation the sprocket chains as they are moved in parallelism by the rotation of the sprocket wheel cause the bearing blocks 22 and 23 to move forward over the base plate, moving the printing roller 100 5 over the printing plates but permitting this printing roller to rotate freely. This rotation of the printing roller is caused by, and is determined by, the contact of the portions 27 and 28 of the roller with the 105 upper surfaces of the guide rails 25 and 26, these portions of the roller being of the same material as that of the portion between them which contacts with the printing surfaces of the printing plates, and of uniform diameter therewith. These portions 27 and 28, being of the relatively soft, rubber-like composition of which the printing roller is necessarily made, tend to cling 110 to the surfaces of the guide rails sufficiently to prevent any slipping on the rails and to ensure the rotation of the roller as it is advanced by the forward movement of the bearing blocks 22 and 23 in the same manner as, but with greater accuracy than, if the guide rails were provided with teeth to form racks and gears were substituted for the portions 27 and 28. 115

120 The printing plates are arranged longitudinally of the base plate 1 in a line parallel with the guide rails 25 and 26, and so 125 that the centres of adjacent plates are at a distance apart exactly equal to the circumference of the printing roller so that the same point on the surface of the printing 130

roller which comes in contact with the centre of the first printing plate will, as the printing roller is rolled onward, come in contact with the centre point of each of the 5 other printing plates in succession, thus ensuring exactness of registry.

It will be understood that the printing surface of each of the printing plates is so cut away as to present only such portion 10 of the design as is to be printed in a particular color the printing plates in this respect being the same as the printing plates used in the ordinary multi-color printing process in which the sheet of paper to be 15 printed is subjected to a separate printing for each color, the sheet being accurately registered for each printing. But, as the printing in the present case is to be done by transfer, the printing plates are positives 20 instead of negatives.

In the drawings, Figures 1 and 1^a, the printing plate 2 is shown as having its printing surface cut away so as to leave only the portion which is to be printed in blue; the 25 printing plate 2' is shown as having its printing surface cut away so as to leave only the portion which is to be printed in red, and the printing plate 2'' is shown as having its printing surface cut away so as to leave only 30 the portion which is to be printed in yellow. It is, of course, to be understood that any other colors may be used.

Between the sprocket wheels the sprocket chains are not supported other than by the 35 printing roller and, though kept under tension sufficient to prevent sagging, will by reason of their flexibility and tendency to sag, keep the printing roller pressed downward upon the guide rails sufficiently to ensure good contact. At the same time the 40 flexibility of the chains permits the roller to rise as it rolls over the printing plates if the printing surface of one or more of the printing plates is above the normal or "type high" level, and also permits the roller to 45 rise slightly in case the article to be printed is of more than usual thickness. By reason of this vertical flexibility of the chains it is rendered unnecessary to adjust the height of 50 the several printing plates to exactly the same level and it is not necessary to make any adjustment of the printing plates or roll to enable the same design to be printed on thick paper or carboard or on very thin 55 paper.

When the bearing blocks 22 and 23 reach the sprocket wheels 13, 13, they, with the printing roller 5, which in its rolling movement over the base plate has taken up the 60 ink from the several printing plates in succession and has deposited the inks so taken up in a complete multicolor design on the sheet or plate or other article in the holder 4, pass down around these sprocket wheels to 65 begin the return movement beneath the base

plate and the cross bar on which it is supported.

As the printing roller reaches the limit of its downward movement its end portions 30 and 31, outside the portions 27 and 28, 70 come in contact with parallel horizontally arranged belts 32 and 33 carried by pulleys 34, 35, and 36, 37, respectively on shafts 38 and 39 one of which shafts, shaft 39 as here shown, is arranged to be driven by any convenient means. These belts 32 and 33 are of such width and are so located that they contact with the outer portions 30 and 31 only of the printing roller 5. These belts are driven in a direction contrary to the direction of movement of the portion of the sprocket chains below the base plate and they are driven at such speed as to cause the printing roller to rotate rapidly, preferably at about 3000 R. P. M. The sag of the 80 sprocket chains ensures good frictional contact of the printing roller with the belts.

As the printing roller thus rotated is carried onward toward the front of the machine by the sprocket chains its surface is 90 brought into contact with the face of a metal disc 40 arranged to rotate in a horizontal plane, that is in a plane perpendicular to the plane of the axis of the printing roller, and carried by a vertical shaft 41 which 95 is arranged to be driven by any convenient means and is preferably hollow. The diameter of this disc is less than the length of the printing roller from end to end but slightly greater than the distance from the outside edge of the portion 27 of the roller to the outside edge of the portion 28 so that the disc will, as the printing roller is moved over its face, be in contact with the mid portion, or printing portion, of the peripheral surface of the roller and also with the portions 27 and 28, and its action upon the surface of the roller will be uniform as regards the portions which bear upon the guide rails as well as the portion which is 100 brought into contact with the printing surfaces of the printing plates in the printing operation. This horizontal disc 40 operates to remove the surplus ink which may remain upon the surface of the printing roller after 105 it has printed the design upon the article to be printed, and to also remove any other foreign matter which may be carried on its surface.

The disc 40 is so located relative to the sprocket wheels 13, 13, that the roller after 110 it has passed over the article to be printed will, by the continued movement of the chains, be brought into contact with the belts 32 and 33 and be rotated rapidly by 115 them, and will be brought into contact, while so rotating, with the surface of the disc 40 on a line parallel with the axis of the roller passing through the centre of the disc. As the roller continues to be moved 120

forward its rapid rotation causes the entire periphery of the roller, except the end portions 30 and 31, to be repeatedly brought into contact with the surface of the rotating disc with the result that all of the ink that may remain on the roller after it has effected the printing will be completely removed.

For the purpose of facilitating this cleaning of the surface of the printing roller a slight quantity of a suitable solvent, such as kerosene, is preferably deposited upon the surface of the disc before or during each cleaning operation. The disc is rotated at relatively slow speed, preferably about 300 R. P. M. Its speed should not be sufficient to cause the ink taken from the surface of the printing roller to be thrown from the surface of the disc by centrifugal action.

The contact of this disc 40 with the surface of the rapidly rotating printing roller is relatively slight, just sufficient to take off the surplus ink and other foreign matter without causing any, or any appreciable abrasion of the surface. But, because it is difficult to avoid some slight abrasion or wear of the roller, it is important that the diameter of the disc should be such as to make this slight abrasion or wear the same on the portions of the roller which bear on the guide rails and determine and control the rotation of the roller in the printing operation as on the portion which acts to take up ink from the printing surfaces of the printing plates as the accuracy of registration depends upon the diameter of the portions 27 and 28 being the same as the diameter of the printing portion of the roller.

The vertical shaft 41 is preferably hollow as stated and is open at its upper end to receive the ink and other foreign matter removed from the printing roller by the disc so as to keep the surface of the disc clean, and a scraper 42 is arranged to guide this matter toward the opening so that this matter will pass down through the hollow shaft into a suitable receptacle below it. By the action of this scraper during the time that the printing roller is not in contact with it the disc will be thoroughly cleaned after each operation ready for subsequent operation.

Between the belts 32 and 33 is arranged means for wiping the surface of the printing roller from which the ink and other foreign matter has been removed by the action of the disc 40. The means here shown for this purpose consists of a broad belt 5 between and with its upper surface in substantially the same plane with the upper surface of the belts 32 and 33, carried by rollers 46, 47 and 48 of which roller 46 is carried on shaft 51 and is positively driven by any convenient means. 47 is a relatively

small guide roller and 48 is a larger roller arranged between the belts 32 and 33 near the disc 40.

This belt 45 is formed of thin slightly absorbent textile fabric supported by a thin flexible sheet of steel 50, here shown as an endless belt passing about the rollers 46, 47 and 28 beneath the belt 45. The belt is driven in the same direction with the belts 32 and 33 but at a slower speed so as to effect a wiping action and at the same time to carry the matter wiped from the roller towards the disc 40. The width of this wiper belt 45 is substantially the same as the diameter of the disc 40 so as to act upon the same portions of the printing roller which are acted upon by the disc, that is, the mid portion and the portions 27 and 28, so that any abrasive action by which the diameter of the printing roller would be reduced will be uniform throughout the printing portion and the portions which bear on the guide rails. The absorbent surface of the wiper belt acts to remove and carry away from the surface of the roller any ink or other foreign matter not removed by the disc 40, as well as any of the kerosene or other solvent taken up from the disc and also acts to polish or freshen up the surface so as to put the surface of the roller in the best possible condition to take up ink from the printing plates and transfer it to the article to be printed.

As the printing roller is carried forward by the sprocket chains and reaches the sprocket wheels 12, 12, it will be lifted off the belts 32 and 33 but as it is carried upward around the sprocket wheels it will continue to rotate at considerable speed by reason of its inertia and in a direction contrary to that in which it is required to rotate in the printing operation. It is therefore necessary to bring its rotation to a complete stop in order that its rotation in the opposite direction by the action of the surfaces of the guide rails upon the portions 27 and 28 may begin. This stopping of its rotation is brought about by contact of the portions 27 and 28 of the roller with the ends of the guide rails 25 and 26 these ends being slightly rounded as shown at 52 and 53 to conform to the curvature of the path in which the printing roller is carried as it is moved around the sprocket wheels. These ends 52 and 53 being of metal are unyielding and if the portions of the roller which are brought against them were also unyielding the shock of contact would be destructive. But, the portions 27 and 28 being of the composition material of which the printing roller is made and which has somewhat the characteristics of soft rubber, serves, by reason of the friction between it and the ends of the guide rails, to absolutely and at once prevent further rotation of the roller and,

by reason of its resiliency, serves to take up or absorb the shock of the sudden stopping without injury to the roller or to the guide rails. As the printing roller is moved onward by the rotation of the sprocket wheels the portions 27 and 28 are brought in contact with the upper surfaces of the guide rails and the roller begins again to roll forward to again take up ink from the printing plates and deposit it upon the article to be printed.

It will be understood that while the printing roller is passing beneath the base plate and being cleaned of superfluous ink and other foreign matter as described the printing plates should be re-inked and the sheet or plate or other article printed should be removed and another one substituted. These operations may be readily effected from either side of the machine, preferably from the side opposite to that on which the pulley 14 is located and should preferably be effected automatically by any convenient form of inking mechanism.

While but three printing plates are here shown it should be understood that any number desired may be used, it being essential only that they be so spaced apart that the distance between their centres shall be exactly equal to the circumference of the transfer printing roller. The base plate will, of course, need to be of sufficient length to provide for the proper spacing of the desired number of printing plates. The printing plates may be of any desired character, electrotypes, etched or engraved plates, lithograph plates, stereotype plates or wood plates. It should further be understood that the roller will need to be of such diameter that its circumference will be not less than the length of any plate measured longitudinally of the base plate.

While the belts 32 and 33 and the wiper belt 45 may be driven by any convenient means the belts 32 and 33 may conveniently be driven by a pulley 90 on shaft 39 driven by belt 91 from any convenient source of power and the wiper belt may conveniently be driven through gear 92 on shaft 11 meshing with gear 93 on stub shaft 94 having secured to it gear 95 which meshes with gear 96 on shaft 46' on which roller 46 is carried.

Having thus described my invention what I claim is:—

1. In a method of transfer printing by means of a transfer roller, arranging a series of printing plates, each having its printing surface formed to print a portion only of a complete design, in line and with the centre points of adjacent plates separated a distance equal to the circumference of the transfer roller, causing the transfer roller to so roll over the printing surfaces of the printing plates that its surface will not have

movement of translation with reference thereto and so that the transfer roller will be free to move vertically and its surface will be held in contact with the printing surfaces of the printing plates by gravity only, causing the transfer roller to roll over the surface of the article to be printed, bringing the surface of the transfer roller into contact with ink removing means and rotating the transfer roller while its surface is in contact with such ink removing means.

2. In a method of printing by transfer, rolling a transfer medium over the inked surface of a printing plate to take up ink therefrom with such regulation of its rotation that its surface will not have movement of translation relative to such inked surface, rolling the transfer medium over the surface of the article to be printed to transfer the ink so taken up onto such surface, and subsequently positively rotating the transfer medium at a relatively high rate of rotation with its surface in contact with ink removing means so that the surface of the transfer medium will move relative to the surface of the ink removing means at a speed greater than the movement of translation of said transfer medium.

3. In a method of printing by transfer, rolling a transfer medium over the inked surface of a printing plate to take up ink therefrom with such regulation of its rotation that its surface will not have movement of translation relative to such inked surface, rolling the transfer medium over the surface of the article to be printed to transfer the ink so taken up onto such surface, and subsequently positively rotating the transfer medium at a relatively high rate of rotation with its surface in contact with ink removing means so that the surface of the transfer medium will move relative to the surface of the ink removing means at a speed greater than the movement of translation of said transfer medium and in a direction opposite to its direction of rotation in taking up ink from the printing plates.

4. In a method of printing by transfer, rolling a transfer medium over the inked surface of a printing plate to take up ink therefrom with such regulation of its rotation that its surface will not have movement of translation relative to such inked surface, rolling the transfer medium over the surface of the article to be printed to transfer the ink so taken up onto such surface, subsequently positively rotating the transfer medium at a relatively high rate of rotation with its surface in contact with ink removing means so that the surface of the transfer medium will move relative to the surface of the ink removing means at a speed greater than the movement of translation of said transfer medium, stopping such positive ro-

- tation of the transfer medium and again causing it to so roll over the printing plate that its surface will not have movement of translation relative to its printing surfaces.
5. In a method of printing by transfer, rolling a transfer medium over the inked surface of a printing plate to take up ink therefrom with such regulation of its rotation that its surface will not have movement of translation relative to such inked surface, rolling the transfer medium over the surface of the article to be printed to transfer the ink so taken up onto such surface, subsequently positively rotating the transfer medium at a relatively high rate of rotation with its surface in contact with ink removing means so that the surface of the transfer medium will move relative to the surface of the ink removing means at a speed greater than the movement of translation of said transfer medium and in a direction opposite to its direction of rotation in taking up ink from the printing plate, stopping such positive rotation of the transfer medium and again causing it to so roll over the printing plate that its surface will not have movement of translation relative to its printing surfaces.
6. In a method of transfer printing by means of a transfer roller of relatively soft, resilient material, causing such transfer roller to roll over the inked surface of a printing plate, regulating the rotation of such transfer roller by contact of a portion of its surface with a fixed surface so that the surface of the roller will not have movement of translation with reference to said inked printing surfaces, causing said transfer roller to roll over the surface of the article to be printed, causing the surface of said transfer roller to be brought into contact with the surface of ink removing means and rotating said transfer roller while its surface is in contact with said ink removing means by contact of a portion of its surface with a moving surface.
7. In a method of transfer printing by means of a transfer roller of relatively soft, resilient material, causing such transfer roller to roll over the inked surface of a printing plate, regulating the rotation of such transfer roller by contact of a portion of its surface with a fixed surface so that the surface of the roller will not have movement of translation with reference to said inked printing surfaces, causing said transfer roller to roll over the surface of the article to be printed, causing the surface of said transfer roller to be brought into contact with the surface of ink removing means, rotating said transfer roller while its surface is in contact with said ink removing means by contact of a portion of its surface with a moving surface, and stopping the rotation imparted to said transfer roller by said moving surface by bringing a portion of the surface of said transfer roller against a fixed abutment of non-resilient material.
8. In a method of transfer printing by means of a transfer roller of relatively soft, resilient material, causing such transfer roller to roll over the inked surface of a printing plate, regulating the rotation of such transfer roller by contact of a portion of its surface with a fixed surface so that the surface of the roller will not have movement of translation with reference to said inked printing surfaces, causing said transfer roller to roll over the surface of the article to be printed, causing the surface of said transfer roller to be brought into contact with the surface of ink removing means, rotating said transfer roller while its surface is in contact with said ink removing means by contact of a portion of its surface with a moving surface, stopping the rotation imparted to said transfer roller by said moving surface by bringing a portion of the surface of said transfer roller against a fixed abutment of non-resilient material, re-inking the surface of the printing plate and again causing the transfer roller to roll over the inked surface of the printing plate.
9. In a method of transfer printing by means of a transfer roller of relatively soft, resilient material, causing such transfer roller to roll over the inked surface of a printing plate, regulating the rotation of such transfer roller by contact of a portion of its surface with a fixed surface so that the surface of the roller will not have movement of translation with reference to said inked printing surfaces, causing said transfer roller to roll over the surface of the article to be printed, causing the surface of said transfer roller to be brought into contact with the surface of ink removing means and rotating said transfer roller while its surface is in contact with said ink removing means in a direction opposite to the direction of its rotation in rolling over the printing plate by contact of a portion of its surface with a moving surface, and stopping the rotation imparted to said transfer roller by said moving surface by bringing a portion of the surface of said transfer roller against a fixed abutment of non-resilient material, re-inking the surface of the printing plate and again causing the transfer roller to roll over the inked surface of the printing plate.
10. In a machine for printing by transfer, a base plate provided on its upper face with parallel longitudinal guide rails, one near each edge, and adapted to support, between the guide rails, printing plates and a holder for an article to be printed, a transfer printing roller adapted to extend across the base plate having its surface of resilient

material adapted to take up ink from the inked surface of a printing plate and having portions of its resilient surface in line with and adapted to engage the guide rails to cause and determine the rotation of the roller as it is moved over the base plate, and means for bodily moving the roller over the base plate and returning it to initial position by a continuous movement, said moving means being adapted to permit free rotation of the roller.

11. In a machine for printing by transfer, a base plate provided on its upper surface with parallel longitudinal guide rails, one near each edge, and adapted to support, between the guide rails, printing plates and a holder for an article to be printed, a transfer printing roller adapted to extend across the base plate having its surface of resilient material adapted to take up ink from the inked surface of a printing plate and provided with means in line with and adapted to engage the guide rails to cause and determine the rotation of the roller as it is moved over the base plate, means for bodily moving the roller over the base plate and returning it to initial position by a continuous movement, said moving means being adapted to permit free rotation of the roller, and means for removing ink from the surface of the roller arranged adjacent to the path of the roller on its return movement and adapted to act upon the surface of the roller during such return movement.

12. In a machine for printing by transfer, a base plate provided on its upper face with parallel longitudinal guide rails, one near each edge, and adapted to support, between the guide rails, printing plates and a holder for an article to be printed, a transfer printing roller adapted to extend across the base plate having its surface of resilient material adapted to take up ink from the inked surface of a printing plate and provided with means in line with and adapted to engage the guide rails to cause and determine the rotation of the roller as it is moved over the base plate, means for bodily moving the roller over the base plate and returning it to initial position by a continuous movement, said moving means being adapted to permit free rotation of the roller, means for removing ink from the surface of the roller arranged adjacent to the path of the roller on its return movement and adapted to act upon the surface of the roller during such return movement, and means for positively rotating the roller while its surface is in contact with said ink removing means.

13. In a machine for printing by transfer, a base plate provided on its upper face with parallel longitudinal guide rails, one near each edge, and adapted to support, between the guide rails, printing plates and a holder for an article to be printed, a transfer print-

ing roller adapted to extend across the base plate having its surface of resilient material adapted to take up ink from the inked surface of a printing plate and provided with means in line with and adapted to engage the guide rails to cause and determine the rotation of the roller as it is moved over the base plate, means for bodily moving the roller over the base plate and returning it to initial position by a continuous movement, said moving means being adapted to permit free rotation of the roller, means for removing ink from the surface of the roller arranged adjacent to the path of the roller on its return movement and adapted to act upon the surface of the roller during such return movement, means for positively rotating the roller while its surface is in contact with said ink removing means, and means for stopping the rotation of the roller on the completion of its return movement.

14. In a machine for printing by transfer, a base plate provided on its upper face with parallel longitudinal guide rails having smooth upper faces, one near each edge, and adapted to support, between the guide rails, printing plates and a holder for an article to be printed, a transfer printing roller having its surface of resilient material adapted to take up ink from the inked surface of a printing plate and of sufficient length to extend across the base plate, having portions of its resilient surface in line with and adapted to bear upon the upper face of the guide rails to cause and determine the rotation of the roller as it is moved over the base plate, means for bodily moving the roller over the base plate adapted to permit the roller, as it is so moved, to be rotated by the contact of its resilient surface with the faces of the guide rails, means for returning the roller to initial position by a continuous movement, and means for cleaning the surface of the roller during its return movement.

15. In a machine for printing by transfer, a base plate provided on its upper face with parallel longitudinal guide rails having smooth upper faces, one near each edge, and adapted to support, between the guide rails, printing plates and a holder for an article to be printed, a transfer printing roller having its surface of resilient material adapted to take up ink from the inked surface of a printing plate and of sufficient length to extend across the base plate, having portions of its resilient surface in line with and adapted to bear upon the upper faces of the guide rails to cause and determine the rotation of the roller as it is moved over the base plate, means for bodily moving the roller over the base plate adapted to permit the roller, as it is so moved, to be rotated by contact of its resilient surface with the faces of the guide rails, means for returning the

- roller to its initial position by a continuous movement, means for cleaning the surface of the roller during its return movement adapted to act equally upon the portions of 5 its resilient surface in line with the guide rails and upon the portion thereof therebetween.
16. In a machine for printing by transfer, a base plate provided on its upper face 10 with parallel longitudinal guide rails having smooth upper faces, one near each edge, and adapted to support, between the guide rails, printing plates and a holder for the articles to be printed, a transfer printing 15 roller having its surface of resilient material adapted to take up ink from the inked surface of a printing plate and of sufficient length to extend across the base plate, having portions of its resilient surface in line 20 with and adapted to bear upon the upper faces of the guide rails to cause and determine the rotation of the roller as it is moved over the base plate and having at its ends 25 portions of its resilient surface outside the lines of the guide rails, means for bodily moving the roller over the base plate adapted to permit the roller, as it is so moved, to be rotated by contact of its resilient 30 surface with the faces of the guide rails and adapted to permit the roller to move vertically, as it is so moved, means for returning the roller to its initial position by a continuous movement, means for 35 cleaning the surface of the roller during its return movement, and means adapted to act upon the end portions of the roller to rotate it while its surface is in contact with the cleaning means. 95
17. In a machine for printing by transfer, a base plate provided on its upper face 40 with parallel longitudinal guide rails having smooth upper faces, one near each edge, and adapted to support, between the guide rails, printing plates and a holder for the article to be printed, a transfer printing roller having its surface of resilient material adapted to take up ink from the inked 45 surface of a printing plate and of sufficient length to extend across the base plate, having portions of its resilient surface in line with and adapted to bear upon the upper 50 faces of the guide rails to cause and determine the rotation of the roller as it is moved over the base plate and having at its ends portions of its resilient surface outside the 55 lines of the guide rails, means for bodily moving the roller over the base plate adapted to permit the roller, as it is so moved, to be rotated by contact of its resilient 60 surface with the faces of the guide rails and adapted to permit the roller to move vertically, as it is so moved, means for returning the roller to its initial position by a continuous movement, means for 65 cleaning the surface of the roller during its return movement, and means adapted to act upon the end portions of the roller to rotate it while its surface is in contact with the cleaning means. 110
18. In a machine for printing by trans-
- fer, a base plate provided on its upper face with parallel longitudinal guide rails having smooth upper faces, one near each edge, and adapted to support, between the guide rails, printing plates and a holder for the 70 article to be printed, a transfer printing roller having its surface of resilient material adapted to take up ink from the inked surface of a printing plate and of sufficient length to extend across the base plate, having portions of its resilient surface in line with and adapted to bear upon the upper 75 faces of the guide rails to cause and determine the rotation of the roller as it is moved over the base plate and having at its ends 80 portions of its resilient surface outside the lines of the guide rails, means for bodily moving the roller over the base plate adapted to permit the roller, as it is so moved, to be rotated by contact of its resilient 85 surface with the faces of the guide rails and adapted to permit the roller to move vertically, as it is so moved, means for returning the roller to its initial position by a continuous movement, means for 90 cleaning the surface of the roller during its return movement, and means adapted to act upon the end portions of the roller to rotate it while its surface is in contact with the cleaning means. 95
19. In a machine for printing by transfer, a base plate provided on its upper face 100 with parallel longitudinal guide rails having smooth upper faces, one near each edge, and adapted to support, between the guide rails, printing plates and a holder for the article to be printed, a transfer printing roller having its surface of resilient material adapted to take up ink from the inked surface of a printing plate and of sufficient 105 length to extend across the base plate, having portions of its resilient surface in line with and adapted to bear upon the upper faces of the guide rails to cause and determine the rotation of the roller as it is moved 110 over the base plate and having at its ends portions of its resilient surface outside the lines of the guide rails, means for bodily moving the roller over the base plate adapted to permit the roller, as it is so moved, to be rotated by contact of its resilient 115 surface with the faces of the guide rails and adapted to permit the roller to move vertically, as it is so moved, means for returning the roller to its initial position by a continuous movement, means for 120 cleaning the surface of the roller during its return movement adapted to act equally upon the portions of resilient surface in line with the guide rails and upon the portion thereof therebetween, and means adapted to act upon the end portions of the roller to rotate it while its surface is in contact with the cleaning means. 125
20. In a machine for printing by transfer, 130

- a transfer roller, a base plate adapted to support printing plates, means for cleaning the surface of the transfer roller arranged below the base plate, a shaft extending across the base plate at each end thereof, endless conveying means carried by said shafts adapted to move the transfer roller bodily over the base plate with its surface in contact with the surfaces of the printing plates 5
- 5 the base plate at each end thereof, endless conveying means carried by said shafts adapted to move the transfer roller bodily over the base plate with its surface in contact with the surfaces of the printing plates and to return the transfer roller beneath the base 60
- 10 and to return the transfer roller beneath the base plate with its surface in contact with the cleaning means.
21. In a machine for printing by transfer, a transfer roller, a base plate adapted to support printing plates, means for cleaning the surface of the transfer roller arranged below the base plate, a shaft extending across the base plate at each end thereof, endless conveying means carried by said shafts adapted 65
- 15 to move the transfer roller bodily over the base plate with its surface in contact with the surfaces of the printing plates and to return the transfer roller beneath the base plate with its surface in contact with the cleaning means, and means below the base plate for rotating the transfer roller during the return movement comprising 70
- 20 belts adapted to engage the surface of the transfer roller.
22. In a machine for printing by transfer, a transfer roller, a base plate, printing plates supported thereon, means for cleaning the surface of the transfer roller arranged below the base plate, a shaft extending across the base plate at each end thereof, endless conveying means carried by said shafts adapted 75
- 25 to move the transfer roller bodily over the base plate with its surface in contact with the surfaces of the printing plates and to return the transfer roller beneath the base plate with its surface in contact with the cleaning means, and means below the base plate for rotating the transfer roller during the return movement. 80
